CLAIM

The ornamental design for a light diffuser, as shown and described.

DESCRIPTION

FIG. 1 is a rear perspective view of the light diffuser showing the new design;

FIG. 2 is a rear view thereof;

FIG. 3 is a front view thereof;

FIG. 4 is a right-side view thereof;

FIG. 5 is a left-side view thereof;

FIG. 6 is a top view thereof;

FIG. 7 is a bottom view thereof;

FIG. 8 is an enlarged rear perspective view of the top part of FIG. 1;

FIG. 9 is an enlarged rear view of the top part of FIG. 2;

FIG. 10 is an enlarged front view of the top part of FIG. 3; and,

FIG. 11 is an enlarged right-side view of the top part of FIG. 4.

The unevenly-spaced broken lines in FIGS. 1-4 and FIGS. 8-11 delineate areas of the figures shown enlarged and form no part of the claimed design.

1 Claim, 10 Drawing Sheets
